UNITED STATES PATENT OFFICE.

CECIL NATHAN, OF WESTMINSTER, LONDON, ENGLAND.

SYSTEM OF BUILDING-BRICKS.

SPECIFICATION forming part of Letters Patent No. 740,683, dated October 6, 1903.

Application filed May 4, 1903. Serial No. 155,588. (No model.)

To all whom it may concern:

Be it known that I, CECIL NATHAN, a subject of the King of Great Britain, residing at No. 39 Victoria street, Westminster, in the county of London, England, have invented a new and useful Improved System of Building-Bricks, of which the following is a specification.

My invention relates to a system characterized by an improved construction of interlocking bricks or building-blocks so devised that when assembled they will be absolutely interlocking, bonding, and immovable.

My bricks or blocks will increase the stability of the building in which they are employed and can be laid with perfect accuracy by unskilled labor. They are consequently of value for buildings of a temporary nature, as well as for permanent structures. The wall or structure composed of such bricks is positively interlocked throughout all its parts by the material of the bricks themselves in addition to the cementing properties of the mortar.

My improved bricks or blocks may be of the ordinary standard or any other convenient size.

My bricks are of two forms mutually interlocking, and a modification thereof forms the quoins, as hereinafter set forth.

Referring to the accompanying drawings, Figure 1 shows the A form or "header" in side elevation. Fig. 2 shows the end view thereof. Fig. 3 shows the B form or "stretcher" in side elevation. Fig. 4 shows the end view thereof; Fig. 5, a side elevation, and Figs. 6 and 7 end views, respectively, of the quoin; Fig. 8, a top view, and Fig. 9 a base view, respectively, of the quoin. Fig. 10 illustrates a modified construction with rounded angles. Fig. 11 is a perspective view of the bricks assembled, showing the bonding.

It will be seen that the headers *a* have two transverse grooves *c* above and one longitudinal groove *d* below, and the stretchers *b* have two transverse grooves *e* above and a longitudinal tongue *f* below.

The quoin *g*, Figs. 5 to 9, interlocks with the adjacent bricks and with the bricks above and below it. The quoin *g* has one cross-groove *h* and one butt-ended slot *i* on top

and corresponding groove *k* and slot *l* in the bottom in reverse positions, Fig. 9.

In Fig. 10 a header *a* and stretcher *b* are shown interlocked. Their projections and slots *c d e f* have rounded angles in this case.

In Fig. 11 the headers and stretchers with rectangular corners are shown interlocked.

The necessity of a quantity of thick mortar is obviated by my construction, and I prefer to use a thin mortar or cement somewhat of the consistency of whitewash applied to the interlocking surfaces. The joins are thus extremely close and no pointing is required.

My improved bricks can be manufactured in the ordinary manner, and the special molds required are simple and involve no further alteration of existing plant.

My bricks may obviously be made of any plastic or other suitable material and hardened in the ordinary way. Bricks of special size, such as half-bricks or bats, are molded to complete angles or fill spaces smaller than the usual size, whereby the need of cutting is dispensed with and a uniform close joining throughout is assured.

Finally my interlocking bricks may be easily set up to form walls without mortar and can be subsequently taken down and set up elsewhere without difficulty or damage to or depreciation of the bricks.

Although in the foregoing description and in the claims it is assumed that the headers are grooved only and the stretchers tongued and grooved, yet the relative arrangement of these might obviously be reversed without departing from my invention.

In commencing a wall it is preferable to lay a row of headers upon the damp course, thereby securing a better seating and alinement.

What I claim is—

1. In a duplex system of interlocking bricks, a superior member having two top transverse grooves and one basal longitudinal groove adapted to interlock throughout its entire length with top projections on one or more inferior members said inferior members having basal tongues adapted to engage with the superior members of a lower row.

2. In a duplex system of interlocking bricks, in combination stretchers sidewise adjacent and breaking joint, superior transverse

grooves and inferior longitudinal tongues on said stretchers, headers basally and longitudinally grooved, each groove adapted to receive the endwise-contiguous projections of 5 two inferior stretchers at one side and the middle projection of the sidewise-contiguous stretcher at the other side, and transverse grooves on the upper surface of said headers, adapted to receive the tongues of a superior row of stretchers.

3. In a duplex system of interlocking bricks, in combination stretchers sidewise adjacent and breaking joint, superior transverse grooves and inferior longitudinal tongues on 15 said stretchers, headers basally and longitudinally grooved, each groove adapted to re-

ceive the endwise-contiguous projections of two inferior stretchers at one side, and the middle projection of the sidewise-contiguous stretcher at the other side, transverse grooves 20 on the upper surface of said headers adapted to receive the tongues of a superior row of stretchers, and quoins adapted to bond with the adjacent bricks and with the bricks above and below.

In testimony whereof I have signed my name to this specification in the presence of two subscribing witnesses.

CECIL NATHAN.
